UNITED STATES PATENT OFFICE.

RUFUS L. JOHNSON, OTHO R. GOOLSBY, AND JOHN N. PHILLIPS, OF EDINBURG,
MISSISSIPPI.

BALING-PRESS.

1,263,322.

Specification of Letters Patent. Patented Apr. 16, 1918.

Application filed February 23, 1916. Serial No. 80,021.

To all whom it may concern:

Be it known that we, RUFUS L. JOHNSON, OTHO R. GOOLSBY, and JOHN N. PHILLIPS, citizens of the United States, residing at 5 Edinburg, in the county of Leake and State of Mississippi, have invented new and useful Improvements in Baling-Presses, of which the following is a specification.

This invention relates to baling presses, 10 and particularly to that class of baling presses which are equipped with rebounding plungers. The invention has for its object to provide simple and improved mechanism for actuating the plunger in the projecting 15 or advancing movement thereof, the retracting movement being caused by an ordinary retracting spring.

A further object of the invention is to produce a simple and improved plunger actuating mechanism, whereby a plurality of plungers pertaining to a plurality of press boxes may be successively actuated in such a fashion that while the motive power will at no time be subjected to excessive strain there 25 will be no waste of power during the intervals of operation.

A further object of the invention is to simplify and improve the construction of the actuating element or master wheel.

With these and other ends in view which will readily appear as the nature of the invention is better understood, the same consists in the improved construction and novel arrangement and combination of parts which 35 will be hereinafter fully described and particularly pointed out in the claim.

In the accompanying drawings has been illustrated a simple and preferred form of the invention, it being, however, understood 40 that no limitation is necessarily made to the precise structural details therein exhibited, but that changes, alterations and modifications within the scope of the claim may be resorted to when desired.

45 In the drawings:—

Figure 1 is a top plan view showing a multiple press including four press boxes, parts of some of which are shown and including four plungers; dotted lines being used to indicate a different relative position 50 of the master wheel and the plungers.

Fig. 2 is a sectional detail view of the press.

Corresponding parts in the several figures 55 are denoted by like characters of reference.

Referring to Figs. 1 and 2, it will be seen that the base B may be composed of a pair of parallel sills 15', said sills being connected at intervals by cross bars 16. The sills support at one end the press box P, a portion 60 of which is shown. The sills also support at the other end thereof a head block 17', having an upwardly extending spindle 18. Guides 19, 20 are mounted on the sills for the purpose of guiding the plunger stem 21 65 which is provided with a laterally extending arm or bracket 22, the same being reinforced by a diagonal brace 23. The master wheel 24 which is mounted for rotation on the spindle 18 is provided with a sweep or lever 70 25, a portion of which extends diametrically across the top surface of the wheel, said sweep being reinforced by a pair of diagonally disposed brace members 26. Extending vertically through each of the braces 26 and 75 through the end of the sweep 25, and also through the thickness of the wheel 24, are pins 28 carrying anti-friction rollers 29, said rollers being obviously disposed at equal intervals about the circumference of 80 the wheel.

When the wheel is revolved by animal or other power applied to the sweep, the rollers 29 will successively engage the lateral arm 22 of the plunger stem 21, which latter 85 will thus be projected against the tension of the retracting spring 30, thus projecting the plunger or follower 31 within the press box. When the roller passes out of engagement with the arm 22, the stem will be retracted by the action of the spring. As long as the master wheel is being rotated the operation will be continued at regular intervals, it being obvious that during the period 90 when the plunger stem is retracted material may be fed to the press in the customary manner.

The head block 17' is mounted at the intersection of the sills in such fashion as to present four sides or faces, each forming an 100 abutment for the arm 22 of a plunger stem 21. The plunger stems are mounted, guided and actuated in precisely the same manner as hereinbefore described, and the parts are designated by the same numerals. It will 105 be seen that by the operation of the master wheel one plunger will be well advanced before the laterally extending arm 22 of another plunger stem is reached by one of the actuating rollers, each plunger being suc- 110

cessively actuated by each of the anti-friction rollers, thereby causing the strain to be evenly distributed in such a fashion that while no excessive strain is at any time encountered, there will on the other hand be no periods or intermissions during which the power is not fully utilized. A battery of presses may thus be operated in a manner calculated to save time as well as power.

10 It will be noted that when the plunger or any one of the plungers is retracted by the action of its retracting spring, the arm 22 will strike and abut upon one of the sides of the head block which is well calculated to 15 resist the shock without being subjected to excessive vibration. By extending the lever or sweep diametrically across the master wheel and reinforcing it with the diagonal braces, a very durable construction is afforded and one which is well calculated to 20 resist the strain on the pins carrying the anti-friction rollers whereby the plungers are directly actuated.

Having thus described the invention, what 25 is claimed as new, is:—

In a device of the class described, a base comprising two pairs of sills crossing each other at right angles and cross bars connect-

ting said sills, a head block mounted at the intersection of the sills having an upwardly 30 extending spindle, said block also having a lower portion which fits between the intersecting sills and in close contact with the same, spring retracted plunger stems guided along the sills and having lateral reinforced arms adapted to abut against the sides of the head block, all of said arms lying in the same horizontal plane, and a master wheel mounted for rotation on the spindle of the head block and having downwardly extending engaging elements, three 35 in number, equidistantly spaced apart, for successive engagement with the lateral arms of the spring retracted plunger stems whereby said stems will be successively actuated 40 against the tension of their retracting springs.

In testimony whereof we affix our signatures in presence of two witnesses.

RUFUS L. JOHNSON.
OTHO R. GOOLSBY.
JOHN N. PHILLIPS.
